[57] CLAIM

The ornamental design for a tent, as shown and described.

DESCRIPTION

FIG. 1 is a front elevational view of a tent showing my new design;

FIG. 2 is a right side elevational view thereof, the side opposite being substantially a mirror image;

FIG. 3 is a rear elevational view thereof;

FIG. 4 is a top plan view thereof;

FIG. 5 is a bottom plan view thereof;

FIG. 6 is a front elevational view of a modified embodiment of the design shown in FIGS. 1 through 5;

FIG. 7 is a rear elevational view thereof;

FIG. 8 is a left side elevational view thereof with portions of the side panels shown in fragment, the side opposite being substantially a mirror image;

FIG. 9 is a top plan view thereof;

FIG. 10 is a bottom plan view thereof; and

FIG. 11 is a perspective view of the lower right hand corner shown in fragment and on an enlarged scale.
